United States Patent Office.

WILLIAM HENRY GROVE, OF PHILADELPHIA, PENNSYLVANIA.

Design No. 4,724, dated March 21, 1871.

DESIGN FOR A SHOW-CASE.

The Schedule referred to in these Letters Patent and making part of the same.

I, WILLIAM HENRY GROVE, of Philadelphia, county of Philadelphia, State of Pennsylvania, have invented or produced a Design for a Show-Case, of which the following is a specification.

In the drawings—

Figure 1 is an end view of a show-case constructed in accordance with my design, and

Figure 2 an end view of a modification.

The design consists of a show-case having a waved front, as plainly illustrated in the drawings.

The back and ends and top and bottom of the case may be vertical and horizontal, and at right angles to each other, or be arranged in any other suitable manner, and the waved front may be rounded at the upper

part, as shown in fig. 1, or may form an angle with the top, as shown in fig. 2.

Irrespective of the shape of the body of the case, I claim—

The design for a show-case, having a waved front, substantially as described, and as represented in and by the accompanying drawings.

In testimony whereof I have signed my name to this specification in the presence of two subscribing witnesses.

W. H. GROVE.
